UNITED STATES PATENT OFFICE.

MATTHIAS F. KNOX, OF NASHVILLE, TENNESSEE.

COMBINED PANEL AND BEAM FOR COMPUTING-SCALES.

SPECIFICATION forming part of Letters Patent No. 729,607, dated June 2, 1903.

Application filed July 19, 1902. Serial No. 116,253. (No model.)

To all whom it may concern:

Be it known that I, MATTHIAS F. KNOX, a citizen of the United States, residing at Nashville, in the county of Davidson and State of

5 Tennessee, have invented certain new and useful Improvements in a Combined Panel and Beam for Computing-Scales; and I do hereby declare the following to be a full, clear, and exact description of the invention, such

10 as will enable others skilled in the art to which it appertains to make and use the same.

This invention relates to an improvement in a beam for computing or price scales, and it is embodied in the construction and arrangement of parts presently to be described, and defined in the claims.

Heretofore it has been suggested to employ a panel for computing-scales in the form of a rotary member having four or more sides on 20 which the computations are placed and associated therewith a single sliding poise. The advantages of the single rotary form is in its wide range of computations. It has also been suggested heretofore to use a flat panel divided into two sections, each of which is 25 provided with a sliding computing-poise.

In both of the structures above referred to an additional or tare beam has been found necessary and detachable weights had also to 30 be employed when large amounts were to be weighed.

The object of my invention is to provide a combined beam and panel which will possess the advantages of the many-sided rotary type 35 of panel in that it will have a large surface area for computations or figures, to provide a panel of peculiar construction well adapted for commercial use and economic manufacture, and to provide a panel which will avoid 40 the necessity of the use of a tare-beam and the use of detachable weights.

A further object of the invention will presently be stated; but in general the design of the invention is a structure which will have 45 a large computing capacity, a capacity for weighing and computing heavy weights at small prices and small weights at high prices, doing away thereby with loose weights and frequent additions by those operating the 50 scale, thus largely avoiding the danger of error and complications.

In the accompanying drawings is shown an

embodiment of the invention; but it is to be understood that various changes can be made without departing from the nature and principle of the invention.

Figure 1 is a front elevation of a combined beam and panel, showing portions of the standard. Fig. 2 is a sectional elevation through the panel and a portion of the frame. 60 Figs. 3, 4, and 5 are detail views of a poise.

A designates the standard of any convenient form of scale, and B designates the shelf or frame, having in the present instance two protecting-uprights B' and B'', the latter having 65 a vertical slot therein, as shown in dotted line, Fig 1. On the shelf B is a fulcrum-pilar C, having a bearing in its upper end.

D designates the connecting-link for the scale-beam.

The panel consists conveniently of a single plate of metal or other suitable material, which is divided into four or more parts 1, 2, 3, and 4, the forward edge of the panel being continuous, while the rear edge is broken 75 by the separating-slots d, extending longitudinally across the panel. These slots are conveniently three in number and are of sufficient width to permit the movement of the upper portion of a poise therein, as will presently be described. To secure the free ends

70 of the plate in their proper positions against deflection or bending and to constitute a support for the panel, an angular rigid metallic frame E is employed, the upright portion e 80 of which and the horizontal portion e' embrace, respectively, the ends of the panels 1 and 2 and the lower edge of the rear portion of panel 2, while the upright portion e'' embraces the ends of panels 3 and 4, which

85 panels are shorter by substantially one-third than are the panels 1 and 2. To make a firm unyielding connection between the panels and the frame E, I have conveniently formed the frame of U-shaped metal, inserting the 90 ends of the members in the space between the portions of the frame and there clamping or securing the panel portions by screws or rivets, as at e³. By this particular construction a supporting member or frame for the panel is 95 provided, which retains the respective panels in their proper positions relative to each other and adds the requisite rigidity to the panel structure.

100 On the end of the panel 3 or pro-

- jecting from the unbroken edge of the panel is a tongue F, entering into the slot of the standard B², which latter thereby acts as a guide for the swinging movement of the beam.
- 5 Fixedly secured to the frame E is the adjusting-poise G and the scale-pan poise 8', the latter being arranged between the rod D and the pillar C. The horizontal portion of the frame E is provided with knife-edges K K', connecting the panel with the pillar C and the link D.
- On the faces of the various panels 1, 2, 3, and 4 are placed suitable indicating marks or figures, the special arrangement of which may not be here illustrated or described, as 15 any well-known and accepted arrangement of figures can be employed. Mounted on the respective panels are the computing-poises 5, 6, 7, and 8, varying in weight from the top to the bottom.
- 20 The computing-poises 5, 6, 7, and 8 are fashioned to fit the opposite sides of the panel to which they belong, being substantially U-shaped. The connecting portion of the poise is projected through the slots d of the panel 25 and are prevented from escaping from the slots. These poises are of varying widths—that is to say, the upper poise is of greater width than the next, and so on. The poises are formed conveniently with pointing fingers 30 L, arranged along their edges and directed, respectively, toward the various lines of figures on the panels. The weight 5 may be of a width greater than that of weight 6, and so on, so as to secure the proper variance in 35 weight, or the weight-poises can be made, respectively, of different thicknesses. Each poise is provided on its side with a knob or operating projection M. To prevent the upper poise from escaping from the panel, the 40 space between the panels 1 and 2 is slightly enlarged, so that the lower end of the poise may project below the panel, as shown in Fig. 2, and its sides connected both above and below the panel, the poises being placed on the 45 panels prior to the securing of the panel ends to the frame E. In each instance I have found it convenient to form the inner face of the poise with recesses N, terminating a short distance from the ends of the poise. This 50 construction while resulting in holding the poise in its proper position on the beam or panel prevents the poise from coming in contact with the figured sides of the beam.
- From the above-described construction it 55 will be observed that a beam of large capacity is formed, on which a great variety of figures can be placed. The division of the panel and the poises can be arbitrary, according to the use for which the scale is intended. One 60 or more of the poises can be used at the same time, and the upper edges of the panels may be spaced to constitute regular scale-indications for tare purposes, while the various panels may be so subdivided that the upper 65 one can be employed for weighing and computing large weights at small prices and the lower one small weights at large prices and

the intermediate panel for intermediate proportions and weights.

The construction above described relates 70 wholly to the structural part of the invention and not to the arrangement of figures or charts; for the reason that I do not wish to be limited to any particular arrangement of charting or figuring of the poises. 75

In practice I have found that the panels may be of aluminium or other light metal and will be highly satisfactory, especially when connected with the scale mechanism through the instrumentality of a rigid frame member, 80 as described.

The object of having the various poises of varying or graduated widths is that the same may be employed in lieu of the ordinary detachable weights, the movement of the poise 85 toward or from the fulcrum securing the desired effect—as, for instance, the poise 8 can readily be moved to the extreme right, while the poise 7, if necessary, could be moved to a point immediately above or any fraction of 90 the distance, and so on, the edge of the panel being properly scaled to indicate the weight as the poise is moved.

Having thus described the invention, what is claimed as new, and desired to be secured 95 by Letters Patent, is—

1. A beam for computing-scales comprising a series of panels united at one of their ends, a reinforcing rigid supporting edge at the opposite ends, a fulcrum on the reinforced 100 edge and poise on the respective panels.

2. A beam for computing-scales comprising a series of computing-panels arranged one directly above the other, and united at their ends, the upper panel being longer than the 105 lower panel, and a reinforcing supporting edge on the horizontal edge of the upper panel and vertical edge of the lower panel carrying a fulcrum extension.

3. A beam for computing-scales comprising 110 a series of computing-panels, a series of computing-panels above said other panels and extending longitudinally beyond the same, and an angular reinforcing-stop extending along the vertical edges of the panels and the horizontal edge of the lowermost upper panel. 115

4. A sectional scale-beam comprising a plurality of separated computing-panels arranged one above the other, the uppermost panels extending longitudinally beyond the 120 lower panels, means for regularly uniting the panels and a reinforcing-strip on the lower edge of the downmost upper panel having knife-edges thereon.

5. In computing-scales the combination 125 with a fulcrum member, of a beam consisting of a plate having a series of slots extending longitudinally thereof and a reinforcing supporting-strip secured to the edge of the beam, and having a knife-edge resting on the fulcrum; substantially as described.

6. A computing-beam consisting of a plate divided into a plurality of sections each having a poise thereon, and a rigid supporting

member of substantially **U** shape in cross-section embracing and secured to the edge of the beam; substantially as described.

7. A beam for computing-scales consisting of a plate having longitudinal slots extending from a point adjacent to its forward edge, dividing the same into a series of separated panels, poised on the panels, and a rigid securing-frame connecting the free ends of the

sections and supporting the beam; substantially as described.

In testimony whereof I affix my signature in presence of two witnesses.

MATTHIAS F. KNOX.
